UNITED STATES PATENT OFFICE.

EDWIN E. BARNEY, OF NEW ROCHELLE, NEW YORK, ASSIGNOR TO REMINGTON TYPE-
WRITER COMPANY, OF ILION, NEW YORK, A CORPORATION OF NEW YORK.

TYPEWRITING MACHINE.

Application filed July 12, 1923. Serial No. 650,996.

To all whom it may concern:

Be it known that I, EDWIN E. BARNEY, citizen of the United States, and resident of New Rochelle, in the county of West-
5 chester and State of New York, have invented certain new and useful Improvements in Typewriting Machines, of which the following is a specification.

My invention relates to typewriting and
10 like machines, and more particularly to carriage escapement mechanism therefor. Ordinarily, a single escapement rack or wheel is driven or advanced by the carriage, and by the power employed to move
15 the carriage in its letter feed movements. The feed rack or wheel in such constructions is therefore fed in unison with the carriage and cannot move to advance the carriage ahead of the latter. It often results
20 in constructions of the character specified that an operator may write two or more letters at the same point, or substantially the same point, on the paper before the carriage has had time to move the requisite
25 distance to provide a separate letter space for each character written. In these circumstances it is difficult to correct an improperly written word, since there is not sufficient room to insert the word that it
30 was intended to write in the space occupied by the erroneously written word with the piled or doubled letters therein. In certain classes of work, where accuracy of spacing is essential, this defect is quite annoying
35 since it may require the entire re-writing of a large sheet.

One of the main objects of my invention is to overcome this defect and to provide a simple, highly efficient and rapid escapement mechanism by which each character written will be accorded a full letter space, no matter how sluggish the movement of the carriage may be. While this may not prevent the piling or doubling of letters, it will nevertheless provide a space for each character written, so that after erasing an improperly written word with piled letters the proper word may be written in place thereof.

50 A further object of my invention is to provide an escapement mechanism of the character specified that may be readily embodied in existing typewriting machines, such, for example, as the Nos. 10 and 11 Remington machines, without materially

modifying the structural features thereof as they now exist.

To the above and other ends which will hereinafter appear, my invention consists in the features of construction, arrangements of parts and combinations of devices set forth in the following description and particularly pointed out in the appended claims.

In the accompanying drawings, wherein 65 like reference characters indicate corresponding parts in the different views,

Figure 1 is a fragmentary fore-and-aft vertical sectional view of an improved No. 10 Remington machine equipped with the 70 devices of my invention; the section through the escapement mechanism in said view being taken on the line 1—1 of Fig. 5, and looking in the direction of the arrows at said line.

Figure 2 is a fragmentary face view of a work sheet with characters on an enlarged scale written thereon to aid in arriving at an understanding of the invention.

Figures 3-6, inclusive, are enlarged detail fragmentary rear elevations with parts in section of the escapement mechanism and associated features; the views indicating the variation in the operation of the escapement under varying conditions of use.

I have shown my invention in the present instance embodied in an improved No. 10 Remington machine but have illustrated only so much of said machine as is necessary to arrive at an understanding of the 90 invention in its inclusion therein. It should be understood, however, that the invention is not restricted to embodiment in such machines but may be used in typewriting and like machines generally, wherever found 95 available.

The frame of the machine comprises a base 1, corner posts 2, and a top plate 3. A carriage 4 is mounted in the usual manner to travel over the top plate from side to side of the machine and carries a platen 5. The carriage is power driven, being propelled in the direction of its feed, or from right to left, by a spring drum 6 connected to the carriage by a pull band 7 and held against movement in the direction of its feed by the escapement mechanism.

In the present instance the dogs by which the feed of the carriage is controlled are, or may be, constructed and operated in the 110

usual manner. Thus there is a holding dog 8 fixed on a pivoted dog rocker 9, and a stepping dog 10 normally engaged by the escapement wheel is pivoted at 11 on the dog rocker. A spring 12 is connected at one end to a pin on the dog rocker 9 and at the other end to an arm on the stepping dog 10 to advance the latter when it is released from the escapement wheel on the down stroke of a key. On the return movement of the key the dog rocker will be returned to normal position by its spring 9^a, and the escapement wheel will be released from the holding dog 8 and the stepping dog will be thrown into the path of the next advancing tooth of the wheel. As the carriage advances one step or letter space distance the escapement wheel bearing against the stepping dog will return it to normal position against the force of its spring 12.

The dog rocker may be controlled by any suitable means from the printing keys 13 and the space key 14. In the present instance each type bar 15 has an engaging edge or projection 16 at its heel which coacts with the universal bar 17 to move the latter rearwardly as the type bar approaches the printing position on the depression of a printing key. This movement is transmitted to the dog rocker through an intermediate train of connections including arms 18 on the universal bar connected at their rear ends to arms 19 on a rock shaft 20. A centrally disposed arm 21 on this rock shaft is operatively connected with the forward end of an actuating link 22, which in turn is operatively connected at its rear end with a headed pin 23 carried by the dog rocker.

Motion is transmitted from the space key to the dog rocker through the arms 24 which support said key and are fixed to a rock shaft 25. A centrally disposed arm 26 fixed to this shaft carries an adjustable member 27. Said member 27 is operatively connected with the lever 28, pivoted at 29, to a bracket 30; the upper end of said lever extending in front of the lug 31 on the link 22. A depression of the space key transmits a rearward movement to the link 22, thus rocking the dog rocker.

In the present instance feed movement is transmitted to the escapement wheel from the carriage as follows: A feed rack 32 is carried by the carriage by arms 33 pivoted at 34 on the carriage. The feed rack meshes with the feed pinion 35 that is adapted to turn with a supporting shaft 36 during the forward feed of the carriage, and to turn independently of the shaft during the return movement of the carriage. The shaft 36 is mounted to turn on a fixed axis in bearings 36^a carried by a rigid bracket. The feed pinion is connected through an intermediate sleeve 37 with a wheel 38 hav-

ing internal ratchet teeth with which the usual backing pawl 38^a engages. This pawl is pivoted on a pin 39 secured to a rotative member, support or carrier 40 that has a hub 41 secured to the shaft 36 by screws 42, 70 a single escapement wheel 43 being mounted on the rotative member 40. The escapement wheel is thus mounted to turn on a fixed axis and is held against bodily movement.

As thus far described the construction is like that employed in the improved No. 10 and the No. 12 Remington machines. However, in such machines the escapement wheel is fixedly connected to the rotative member 40, and is driven wholly by the power employed to move the carriage and cannot advance independently thereof. In accordance with my present invention the escapement wheel is mounted on the member 40 so as to be capable of having a limited independent advance movement thereon for purposes which will hereinafter appear. Thus the escapement wheel 43 is provided with bearing portions 44 by which the wheel is rotatively supported on a circular, 80 shouldered bearing portion 45 of the member 40. The body portion of the escapement wheel has three concentrically arranged slots 46 therein, and also has the usual single series of peripheral teeth *a*, *b*, *c*, *d*, etc. Extending through each slot 46 is a stem of a headed and shouldered screw 47 received at its threaded end in a tapped opening in the member 40. The head of each screw 47 overlaps the body of the wheel and holds it against rearward displacement from its supporting member or carrier 40, whereas the shouldered stem of each screw coacts with the end walls 48 and 49 of the slot 46 in which it is received to limit the rotative movement of the wheel relatively to its carrier 40. In the present instance the extent of lost motion, due to the pin and slot connection between the escapement wheel and its carrier, corresponds to three teeth of the escapement wheel, or three letter space steps of the carriage, although this distance may be varied according to conditions, as will presently appear. A coiled contractile spring 50 is connected at one end to one of the screws 42, whereas the other end of said spring is connected to a pin 51 which projects from the rear side of the escapement wheel. The spring 50 thus connects the escapement wheel with the rotative member 40, and the force of the spring tends to advance the wheel relatively to said member 40 from the normal position shown in Fig. 3, to any one of the positions shown in Figs. 4, 5 and 6, depending on circumstances. This enables the escapement wheel to be rapidly advanced by the spring 50 a letter space distance at each complete operation of a printing key or the space key, and to receive such move-

ment ahead of the feed movement of the carriage if the latter should for any reason be slow or sluggish, or the keys should be operated at a higher speed than the movement of the carriage can respond to. Such sluggish movement of the carriage may be due to excessive weight thereof, to low pressure exerted by the carriage spring, or to undue resistance offered to the movement of the carriage. A more detailed description of the operation of this construction and certain of the advantages which flow from its use will now be set forth. Where the conditions are ideal in typewriting machines generally, and the operator is not too rapid or erratic in operating the machine, the writing produced on the work sheet should appear as indicated in the first line 52 of the work sheet 53, shown in Fig. 2. It will be observed that in this line there are no piled up or doubled characters, each character written being accorded its proper space and position in the line. However, there are few, if any, machines in which, at times and under certain conditions, the characters will not be piled up as indicated at 54 in the second line 55. This line represents the repeated word "work" with piled letters at 54, substantially as they appear when written on a machine in which the escapement wheel or rack moves in unison with the feed of the carriage. Each of the dotted lines 56 represents a letter space position. It will be observed that there are sixteen of these dotted lines, each representing a letter space position of the word "work," written four times in the first line where each letter is accorded its proper space. It will be seen, however, that in the second line the first sixteen characters are crowded into twelve spaces and that there is insufficient room to correctly re-write the word "work" four times within the allotted twelve spaces. The third line 57 indicates the word "work" assumed to be written four times on a machine embodying the present invention, and wherein two piled letters appear at each point 58 and three piled letters appear at the point 59. It will be seen that in this line a space is recorded for each written character even though in five instances two or more letters are piled one on top of another. If, therefore, this erroneously written matter is erased, the word "work" may be written four times in the allotted sixteen spaces; the re-writing appearing as it is represented in the first line 52 on the work sheet.

I will now describe more in detail just how the escapement acts to accord a letter space to each character written even though certain of the characters be piled one on top of another. Referring particularly to Figs. 3-6, inclusive, it should be understood that Fig. 3 shows the parts as they appear in the normal position, or when at rest. If the speed of the carriage is sufficient to meet the requirements of the operator, and is as fast as that of the escapement wheel, then motion transmitted from the carriage through the feed rack 32, feed pinion 35 and the rotative member 40 will cause the escapement wheel to move in unison with the carriage and the characters may be written without piling or doubling, as indicated in the first line 52 on the work sheet. However, it is seldom that the comparatively heavy carriage, and the train of operative connections from the carriage to the escapement wheel, can be moved as rapidly as the light escapement wheel under the action of its spring 50. In most instances, therefore, the escapement wheel will be advanced by its spring 50 ahead of the rotative member 40 and the carriage which controls the advance movement of the latter. The extent of this advance of the escapement wheel over the carriage controlled member 40 will vary, depending on circumstances. In order that this may be made clear I have shown in Figs. 4, 5 and 6, three different extents of independent advance movement of the escapement wheel corresponding respectively to one, two and three letter spaces. I have assumed for simplicity of illustration that the carriage has not moved at all while a single operation of a key permits an independent advance movement of the escapement wheel from the Fig. 3 to the Fig. 4 position under the action of its spring 50; the feed rack 32 and the carriage subsequently advancing from the full to the dotted line positions shown in Fig. 4, or one letter space. In Fig. 5 I have assumed that the escapement wheel has moved two steps in advance of the carriage, or from the Fig. 1 to the Fig. 5 position by two successive operations of a printing key or the space key; the feed rack and carriage subsequently moving two letter spaces from the full to the dotted line position indicated in Fig. 5. Fig. 6 represents an independent advance movement of the escapement wheel three steps or letter space distances beyond the Fig. 3 position at three successive operations of a key; the carriage and feed rack moving subsequently from the full to the dotted line position in Fig. 6, or the distance of three teeth of the feed rack. I have represented the feed rack and carriage as standing still while the escapement wheel turns under control of the keys relatively to the carriage controlled member 40 from the Fig. 3 to the Figs. 4, 5 and 6 positions, for a relative advance of one, two or three teeth respectively, as may occur if the carriage is held against advance movement. Nevertheless, it will be understood that in practice the carriage may be advancing at the same time as the escapement wheel but

at a lower rate of speed. Thus while it may be possible under certain conditions to write two and even three characters, one on top of another, or substantially so, while the carriage is advancing but one space in a machine of the character described, it is believed not to be possible to write more than three characters in such a machine while the carriage is advancing but one space. Moreover, three characters may be written substantially one on top of another in such a machine only when it is operated under the most disadvantageous conditions. Of course the more sluggish the movement of the carriage, the more apt is a speedy operator to double the letters. Sluggishness in the movement of the carriage may be due to its weight, to the amount of power employed to move it, to the resistance offered to the movement of the carriage, etc., etc. However, practice has demonstrated that in the machine in which the invention has been embodied, an extreme independent advance movement of the escapement wheel for three letter spaces will suffice for the most disadvantageous conditions of use. Such a condition is encountered, for example, when the carriage spring is reduced to its lowest point of effectiveness, when the carriage employed is a comparatively heavy one, and the machine is given the severest test by the speediest of operators. Such extreme conditions are seldom met with in practice but are given to illustrate the accuracy of feed of the escapement wheel under the most adverse of conditions. From what has been said it will be understood that the extreme extent of independent movement required of the escapement wheel may be varied considerably, depending on circumstances; such as the character of the machine in which the invention may be employed, the weight of the carriage and parts driven thereby to turn the escapement wheel, the amount of resistance offered to the movement of such parts, the amount of power employed to move the carriage, the resistance offered, if any, to the movement of the carriage by the ribbon feed and reversing means, the bell trip, line lock, etc. Therefore, while I have in the present instance disclosed a construction in which the extreme independent advance of the escapement wheel is three letter spaces, this amount may be varied as required by the conditions presented and the particular character of typewriting machine in which the invention is embodied. The extreme amount of independent movement of the wheel, indicated herein, is sufficient to meet the severest condition of use in a machine of the character in which the invention is shown embodied.

In order to prevent a backward movement of the escapement wheel when the carriage is returned to the right, and thus maintain

a proper relation between the feed dogs and wheel to accord with the reading of the carriage scale, I employ a back holding pawl 60. This pawl is pivoted at 61 on a lug or bracket arm 62 that extends up from the bracket 63 by which the bearings 36^a for the escapement wheel shaft 36 are supported. This is preferably a gravity pawl, the engaging nose 64 of which is adapted to engage teeth 65 formed in the periphery of the rotative carrier 40. A hook-like engaging member 66 is formed on the pawl and co-acts with the bracket 63 to limit the pivotal movement of the pawl away from the engaging position, and thus prevent the pawl from being turned to a position where it may not properly act by gravity to coact with the teeth 65 when the machine is in use.

When the carriage is drawn back to the right, the feed pinion 35 and the wheel 38 receive a backward rotation independently of the shaft 36 and the escapement wheel. The pawl 38^a at this time enables such independent movement of the pinion 35 and the wheel 38 to take place, while the member 40 and the escapement wheel shaft are held against backward movement by the pawl 60.

It will be understood from what has been said that the invention as it is disclosed in the present instance may be readily embodied in an improved No. 10 or in a No. 12 Remington machine without materially modifying the structural features of said machine as they now exist, the changes in the main consisting in connecting the escapement wheel to its carrier 40 by a lost motion connection 46, 47 and the addition of the spring 50 to advance such wheel independently of the carrier.

Various changes may be made without departing from the spirit of my invention.

What I claim as new and desire to secure by Letters Patent, is:—

1. In a typewriting machine, the combination of a power driven carriage, and escapement mechanism comprising an escapement wheel held against bodily movement, and means for advancing said escapement wheel rotatively in the direction of its feed relatively to the advance of the carriage for more than a letter space distance in the ordinary control of the escapement wheel by the printing or space keys, one letter space advance of the wheel being effected at each actuation of one of said keys.

2. In a typewriting machine, the combination of a power driven carriage, and escapement mechanism comprising an escapement wheel held against bodily movement, a holding dog, a stepping dog, and means which enable the escapement wheel to be advanced relatively to the advance of the carriage during the control of said wheel by the feed dogs.

3. In a typewriting machine, the combina-

tion of a power driven carriage, and escapement mechanism comprising an escapement wheel, a feed rack carried by the carriage, a feed pinion with which said rack meshes, 5 a lost motion connection between said feed pinion and escapement wheel, a spring which tends to advance the escapement wheel to the limit of said lost motion connection, a stepping dog, and a holding dog co-operative with said escapement wheel.

4. In a typewriting machine, the combination of a power driven carriage; and escapement mechanism which permits letter feed advance of the escapement relatively 15 to the carriage, comprising a single escapement wheel that turns on a fixed axis, feed dogs that coact therewith, and means adapted to bring about a complete letter space advance of the escapement wheel ahead of 20 a complete letter feed of the carriage by a power independent of that employed to move the carriage.

5. In a typewriting machine, the combination of a power driven carriage; and escapement mechanism which permits letter feed 25 advance of the escapement relatively to the carriage comprising a single escapement wheel that turns on a fixed axis, feed dogs that coact therewith, intermediate driving 30 connections between the carriage and said escapement wheel including a lost motion connection that permits the escapement wheel to advance a full letter space independently of and ahead of the carriage, and 35 a spring for thus advancing said wheel.

6. In a typewriting machine, the combination of a power driven carriage; and escapement mechanism comprising an escapement wheel which turns on a fixed axis and 40 is turned by the power employed to move the carriage, means which enable said wheel to be advanced before the carriage advances, and stepping and holding dogs coacting with said wheel.

45 7. In a typewriting machine, the combination of a power driven carriage, a feed rack carried thereby, a feed pinion turned by said rack, an escapement wheel, a lost motion connection between said feed pinion and escapement wheel that enables the latter to advance independently of the feed pinion a limited distance, a spring connected to said escapement wheel for effecting said independent advance movement thereof, and 50 stepping and holding dogs coacting with said wheel.

8. In a typewriting machine, the combination of a power driven carriage, an escapement wheel that turns on a fixed axis and 60 each step-by-step advance movement of which under control of the keys determines the advance of the carriage one letter space, and means whereby said wheel may be advanced under control of the keys independently of the carriage more than a single step.

9. In a typewriting machine, the combination of a power driven carriage, a feed rack carried thereby, a feed pinion with which said rack meshes, a rotative member operatively connected to turn with said feed pinion as the carriage moves in a letter feed direction, an escapement wheel connected to turn with said rotative member and to advance independently thereof for a limited distance, a spring connected to said rotative member and to the escapement wheel and operative to effect said independent advance movement of the latter, and stepping and holding dogs which coact with the escapement wheel.

10. In a typewriting machine, the combination of a power driven carriage, a rotative member turned by the advance movement of the carriage, a single escapement wheel so connected with said rotative member 80 that the two will turn together and the escapement wheel may advance a limited distance relatively to said member, and a spring between said rotative member and escapement wheel for effecting such relative advance movement of the escapement wheel whereby the escapement wheel may turn a full letter space distance before the carriage is fed a like distance.

11. In a typewriting machine, the combination of a power driven carriage, a rotative member operatively connected to the carriage to be turned by the feed movement of the carriage and permit a return movement of the carriage without turning said member, an escapement wheel so connected with said rotative member that the two will turn together and the wheel may advance relatively to said member a limited distance of more than a letter space, teeth on said rotative member, and a pawl that engages said teeth and prevents a backward rotation of said member when the carriage is moved backward.

12. In a typewriting machine, the combination of a power driven carriage, a feed rack carried thereby, a feed pinion driven by said rack, a rotative member, a pawl and ratchet intermediate said pinion and rotative member to cause the latter to be turned by the advance of the carriage and permit a return movement of the carriage without turning the rotative member, an escapement wheel connected to said rotative member by a lost motion connection which enables the escapement wheel to be advanced relatively to said rotative member a limited distance, a spring which connects the escapement wheel and said rotative member and effects such relative advance movement of the wheel, and stepping and holding dogs co-operative with said escapement wheel.

13. In a typewriting or like machine, the combination of a power driven carriage, a single escapement wheel that turns on a

fixed axis, and means whereby the said wheel advances a letter space distance at a complete operation of a printing key even though the carriage does not advance a corresponding distance, thus permitting two types to print in one letter space on the paper, said means being so constructed that the carriage will subsequently advance and leave a blank space on the paper for the second character that had been crowded into the space ahead.

14. In a typewriting machine, the combination of a power driven carriage, a single escapement wheel operatively connected thereto, separate power means for advancing said wheel, and means for permitting a complete letter space movement of the escapement wheel by its separate power in advance of a complete letter feed movement of the carriage by its power.

15. In a typewriting machine, the combination of a power driven carriage, a single escapement wheel operatively connected to said carriage, a separate power means for

the escapement wheel, and connections enabling said escapement wheel to advance one or more letter space distances under its own power means independently of the carriage advance under its power, so that under rapid operation of the machine the said escapement wheel may readily respond thereto and in so doing will take an abnormal or advance relation to said carriage; and said connections being such that when the operation of the machine ceases the final movement of the carriage will bring about again the normal or initial relationship between itself and said escapement wheel and said connections.

Signed at the borough of Manhattan, city of New York, in the county of New York, and State of New York, this 9th day of July A. D. 1923.

EDWIN E. BARNEY.
